UNITED STATES PATENT OFFICE.

FRANK E. NELSON, OF LOS ANGELES, CALIFORNIA.

ATOMIZER.

No. 910,144.

Specification of Letters Patent.

Patented Jan. 19, 1909.

Application filed January 31, 1908. Serial No. 413,630.

To all whom it may concern:

Be it known that I, FRANK E. NELSON, citizen of the United States, residing at Los Angeles, in the county of Los Angeles and State of California, have invented new and useful Improvements in Atomizers, of which the following is a specification.

My invention pertains to devices for comminuting hydrocarbon and commingling the same with steam or other fluid under pressure; and it has for its object to provide a device for the purpose stated possessed of high capacity, and one which is simple and inexpensive in construction, is capable of being easily regulated, and is well adapted to withstand the usage to which such devices are ordinarily subjected and to be expeditiously and easily cleaned when necessity demands.

With the foregoing in mind, the nature of the invention and its novelty and utility will be fully understood from the following description and claim when the same are read in connection with the drawings, accompanying and forming part of this specification, in which:

Figure 1 is a view, partly in longitudinal section and partly in elevation, of the device constituting the preferred practical embodiment of my invention. Fig. 2 is a side elevation of the perforated gland of the device, removed. Fig. 3 is a transverse section taken in the plane indicated by the line 3—3 of Fig. 1, looking in the direction indicated by arrow. Fig. 4 is a view showing in front end elevation a slightly modified embodiment of my invention, hereinafter referred to in detail.

Referring by letter to the said drawings, and more particularly to Figs. 1 to 3 thereof: A is the casing of my novel atomizing device, which is preferably of the form illustrated. The said casing is closed at its outer end by a plug a, and is provided at about the point shown with a partition wall b, and is also provided at one side of said partition wall with an orifice c for the entrance of steam and at the opposite side thereof with an orifice d for the entrance of hydrocarbon. At its forward end, the casing A is provided with an eduction opening e, preferably of circular form, while at about the distance shown in rear of said opening it has three (more or less) interior projections f. It will also be noted by reference to Fig. 1 that the

interior of the casing A is tapered or gradually reduced in diameter from the bases of the projections f to the opening e, as indicated by g for a purpose presently set forth.

B is a needle movable rectilinearly in the casing A and having a handle portion h extending rearward through the plug a and also having enlargements i on said handle portion and at opposite sides of the plug a, the purpose of which is to limit the movements of the needle in opposite directions. The portion of the needle in front of the handle portion h is tubular, is provided at j with perforations, and terminates at its forward end in a tapered portion k. At this point attention is directed to the fact that the needle B is guided in the partition wall b and between the projections f of the casing A, and that back of its tapered end k the needle is of a size in cross-section to snugly occupy or fit in the eduction opening e in the forward end of the said casing.

My invention contemplates the conduction of hydrocarbon through the tubular needle B and the conduction of fluid under pressure (preferably steam) through the forward portion of the casing A to the point where the hydrocarbon is atomized and the two commingled, and by reason of the construction just described it will be manifest that the steam in passing out through the opening e will after leaving the device continue in the direction it takes between the tapered wall g and the tapered end k of the needle B, and consequently will cut across the forward end of the needle and catch the hydrocarbon passing out said end and tear it into monoculars, and at the same time will effect a thorough mixture of air with the hydrocarbon. It will also be manifest that the projection of the needle B forward of the casing A precludes mixing of hydrocarbon and steam at any point inside the device, this being advantageous since it prevents wear of the nose or forward end of the device. This latter will be better appreciated when it is remembered that crude oil carries more or less grit and that the grit is set free the instant the hydrocarbon is commingled with steam, and that the liberated grit in passing through a restricted opening like e would grind the metal away and render frequent repairs necessary. It will further be manifest that the volume of steam at e may be regulated by moving the needle

B in the direction of its length and without recourse to the steam supply valve (not shown), and that the orifice around the needle at the forward end of the device may 5 be expeditiously and easily cleaned.

It is essential that the hydrocarbon and steam be kept separated while in the device, and also that leakage of hydrocarbon at the rear end of the device be precluded. To 10 these ends I provide glands C and D, stuffing E between the partition wall *b* and the gland D, and stuffing F intermediate the two glands. The gland D is arranged opposite the hydrocarbon supply orifice *d* and around 15 the perforated portion of the needle B, and in order to assure free passage of hydrocarbon into said needle, the gland is recessed exteriorly and interiorly as indicated by *m* and *n*, respectively, and is provided with a 20 plurality of perforations *p*.

When a flat horizontal flame is desirable I employ the modified construction shown in Fig. 4. This construction is similar to that shown in Figs. 1 and 3, with the exception 25 that it has two opposite grooves M formed, by preference, in the casing A at opposite sides of the eduction orifice *e'*. By virtue of the provision of these grooves M, the two jets of steam meet and flatten out and in 30 that way form a broad horizontal flame; the flatness of the flame being governed by the angle of the nozzle and the position of the needle relative to said nozzle.

The construction herein shown and 35 described constitutes the best embodiment of my invention of which I am cognizant, but it is obvious that in the future practice of the invention such changes or modifications may be made as fairly fall within the scope

of my invention as defined in the claim appended.

Having described my invention, what I claim and desire to secure by Letters-Patent, is:

The herein described device comprising a casing having an eduction opening in its forward end and a bore tapered forwardly to said opening and also having an inlet for steam in its side and an inlet for hydrocarbon in its side at a point in rear of said steam inlet, a plug closing the rear end of the casing and having an opening, a hollow needle extending through said opening in the plug and having enlargements disposed at opposite sides thereof and also having a forward tapered end portion and a portion in rear of the tapered portion, of a diameter to snugly occupy said eduction opening and further having a plurality of small apertures in its portion opposite the hydrocarbon inlet, a gland arranged in the casing opposite the hydrocarbon inlet and receiving said apertured portion of the needle and having an interiorly and exteriorly recessed and apertured portion arranged opposite the hydrocarbon inlet, a partition wall fixed in the casing in front of said gland, packing intermediate the forward end of said gland and partition wall, and packing arranged in the casing in rear of the gland.

In testimony whereof I have hereunto set my hand in presence of two subscribing witnesses.

FRANK E. NELSON.
